DESIGN FOR A CONICAL BUTTON

Charles H. Frank, New Rochelle, N. Y.

Application July 10, 1945, Serial No. 120,615

Term of patent 14 years

(Cl. D17—2)

To all whom it may concern:

Be it known that I, Charles H. Frank, a citizen of the United States, residing in the city of New Rochelle, county of Westchester, State of New York, have invented a new, original, and ornamental Design for a Conical Button, of which the following is a specification, reference being had to the accompanying drawing, forming a part hereof, in which:

Fig. 1 is a top plan view of a conical button showing my new design;

Fig. 2 is a side elevational view thereof; and Fig. 3 is a bottom plan view of my new design.

I claim:

The ornamental design for a conical button, as shown.

CHARLES H. FRANK.
